DIAPER HOUSING

Marion Donovan, Saugatuck, Conn., assignor to:
 Kennedy Car Liner & Bag Co., Inc., Shelbyville, Ind., a corporation of Indiana

Application June 14, 1949, Serial No. 99,096

5 Claims. (Cl. 128—287)

1

This invention relates to new and useful improvements in diaper housings and relates more particularly to a novel unitary encasement for the diaper which substantially completely encloses the diaper and also forms effective fastening means for securing the diaper in place on the wearer. The diaper housing constituting the principal embodiment of the present invention is an improvement on the diaper covers set forth in my co-pending application Serial No. 71,580, filed January 19, 1949, now Patent No. 2,556,800 and Serial No. 91,536, filed May 5, 1949, and the present application constitutes a continuation-in-part of such latter application.

An important object of the invention is to provide a confining and supporting element for a diaper formed in the nature of a housing which encloses its outer surface, its four edges and the marginal portions of its inner surface, and when the unit is in place on the baby the assembly is leak-proof and the leg openings are free and well-ventilated. Thus, the need for safety pins, tying tapes and other fastening devices for the diaper is eliminated and the conventional diaper may be simply folded to proper size and placed within the housing. The complete unit is then adjusted in place on the baby and suitably secured as by snap fasteners. In this fashion, a diaper of usual size can be folded so as to provide many more layers of material than would be the case with the usual folding of the diaper and application by safety pins or the like.

It will be apparent from the foregoing that another object of the invention is to provide a diaper assembly having a greater measure of absorption and wherein the area of the wet diaper which is exposed to the body is very considerably reduced by providing an inner wall construction comprising side flaps and end flaps which cover the four margins of the folded diaper.

Another object of the invention is to provide a diaper housing having an outer wall, side walls, and an inner wall formed from a single blank or from plural blanks which provides an elongated opening of such size as to permit of effective diapering but which encloses the balance of the inner surface of the diaper element, securely supporting the same and effectively shielding such portions, when wet, from the body of the infant.

The entire housing is preferably made from flexible, waterproof material which prevents wetting of the bed or of a chair, in that the housing provides an effective pocket from which no fluid can flow so long as the child is in any usual

2

position. The housing provides a greater measure of freedom for the child than do usual rubber pants or diaper coverings, and since there is no constriction of the parts there is provided a desired measure of ventilation.

Another important object of the invention is to provide a housing of the character described with novel side walls formed from blanks having generally the shape of a catenary curve and whose edges are largely on the bias of the material so as to provide a desired measure of stretchability and also to cause the diaper assembly to hang in a comfortable and non-binding manner when the child is standing or sitting.

15. A further object of the invention is to provide a diaper housing which is readily cleaned by rinsing in warm water and whereas the housing is fully pocketed, convenient drain means are provided in order that it may be simply hung up to dry and retain none of the water in the pockets.

Still another object of the invention is to provide a diaper assembly including a diaper and housing therefor which provides interconnected front and back panels, having laterally extending wing portions which overlap each other and are provided with plural, complementary fastening means arranged in spaced relation at the corners of the housing, any pair of which may be engaged to secure the housing in place and to enable the housing to be used as the child grows.

30. In the drawings:

Fig. 1 is a front and partial side perspective view of a diaper housing embodying my invention.

35. Fig. 2 is a vertical section taken on line 2—2 of Fig. 1.

Fig. 3 is a plan view of the inner surface of the diaper housing.

Fig. 4 is a plan view of the outer surface thereof.

40. Fig. 5 is a section taken on line 5—5 of Fig. 3.

Fig. 6 is a plan view of the blank used in forming the outer wall of the housing.

Fig. 7 is a plan view of the back flap.

Fig. 8 is a plan view of the blank used in forming the front flap.

45. Fig. 9 is a plan view of the blank used in forming each side wall.

Fig. 10 is a plan view of the blank used in forming each side flap.

50. Fig. 11 is a plan view of a second embodiment having integrally formed end flaps.

Fig. 12 is a plan view of a further embodiment having a one-piece inner wall.

The pattern of the diaper housing forming a preferred embodiment of the present invention is

shown in Figs. 6 to 10 inclusive and includes an elongated blank 10 forming the outer wall. This blank is provided with a rear edge 11, and a front edge 12 of lesser length than edge 11, both of such edges being joined by concavely curved edges 13, the curves flattening out as they approach their terminals as shown at 14.

A rear flap 15 has two generally parallel edges 16 and 17 and angular edge sections 18 and 19 at each end thereof. Edges 16 and 17, which are of substantially equal length, are shorter than rear edge 11.

A front flap 23 of generally the same shape as blank 15 is provided with opposed generally parallel edges 24 and 28 the latter being the longer of the two, and angular edge sections 25-26 at each end thereof.

A fourth blank 27, two of which are used, has an inner concave edge 31, an opposed, generally straight edge 29, both joined by short edges 30.

Finally, blank 34, forms a side wall, one on each side of the housing, and is of generally the shape of a catenary curve with opposed edges 35-36, both joined at their ends by short edges 37. Lines which are tangent to the central portions of edges 35-36 would be generally parallel with the grain line of the material.

In assembling the diaper housing a tuck 40 is first formed in the rear section leading inwardly from edge 11. The rear flap 15 is folded along broken line 41 to form the upper edge 42 of the housing. Edge 11 of blank 10 is next stitched to blank 15 forming stitch line 43 which extends through both layers of the flap. The inner section 44 of the rear flap now overlays a portion of the inner surface of the outer wall 10.

Blank 23 is now folded along line 45 to form the upper front edge 46 and edge 28 is stitched to blank 10 to form stitch line 47 which also extends through both layers of the material. The fold line 45 of blank 23 is of substantially the same length as edge 12 of blank 10 and when assembled, is positioned adjacent thereto. The remaining section 51 forms the inner front flap.

The outer curved edge 36 of each side wall blank is now secured to outer wall 10 as by means of stitching along straight lines 52 shown in Fig. 6 forming stitch line 56. The ends 37 of these side wall blanks are left free and unattached for a reason presently to be discussed.

The inner curved edges 35 of side wall blanks 34 are now stitched to the straight edges 29 of side flap blanks 27 to form stitch line 57. Finally the terminal edges 30 of the latter blanks are stitched to the inner surface of end flaps 44 and 51, forming stitch lines 61. Complemental fastening means 62 are disposed in spaced relation at each corner section of the housing and as the child grows the fasteners nearer the corner section may be used.

In Fig. 3 these fasteners are shown as being substantially equally spaced from upper edges 42-46 whereas in Fig. 4 these fasteners 62' are disposed progressively nearer the corner sections to allow for a more rounded opening for the legs as the child grows.

By leaving the terminal edges 37 of side walls 23 free and unattached the housing may be easily washed and rinsed and then hung up to thoroughly dry, such edges forming openings for an otherwise closed pocket. This pocket is defined by stitch lines 56-57 along each side of the housing and 43-47 at opposed ends thereof. Extending inwardly from these stitch lines are the side flaps 27 and the front and rear flaps 51-44.

This defines a substantially rectangular compartment for the diaper 60 (Figs. 2 and 5).

In use the diaper is first folded to proper shape and is then inserted under the side walls and flaps. Thus, a substantial portion of the margins of the inner surface of the diaper are covered with waterproof material, leaving the central, elongated section exposed for effective diapering. The front section defined by the overlapping flaps 23-51 is slightly more narrow than the rear section which makes application of the diaper assembly to the squirming child easier.

In Fig. 1 the wing terminals of the front section are shown as overlapping the wing terminals of the rear section. This arrangement may, of course, be reversed.

It was earlier pointed out that the outer, concavely curved edges 36 of the side wall members 34 are stitched along straight lines 52 of outer wall blank 10 to form stitch line 56. When the housing is in the flat position of Figs. 3 and 4 this curved edge-straight edge relationship has a tendency to have a gathering effect in the housing which is of no consequence. When, however, the diaper is in the position of Figs. 1 and 2 the straight line 52 has assumed a concavely curved contour integrating it with the curved edge 36 of the side wall. Similarly, the outer curved edge 35 of the side wall is joined to a straight edge 29 of the inner wall 27 which has the same effect.

In the modified arrangement of Fig. 11 the outer wall 65 and the end flaps 66 and 67 are formed integrally rather than in separate pieces as in the first embodiment, the broken lines 68-69 showing the initial contour of the outer blank. It will also be noted that the grain line of the material has been rotated approximately 45° from that shown in the first embodiment. In this instance, the terminal sections are folded along lines 70-71 to form the front and back upper edges, respectively, of the housing. The side walls 72-73 may be formed from blanks similar to that shown in Fig. 9.

The side flaps 74-75 are of the shape shown 45 and have overlapping portions 76-77 at the ends of the housing. The outer longitudinal edges of the side flaps are shown as being concavely curved rather than straight as in the first embodiment. The end flap portions 66-67 are stitched to the outer wall portion along stitch line 81. In this instance, again the short terminal edges of the side walls 72-73 may be left free and unattached to form openings for drainage in laundering. Snap fasteners 82 are secured at the four corners of the housing. This particular construction has many of the same advantages as the first embodiment and is less expensive to construct.

The diaper (not shown) is inserted in the housing in the same fashion as in the first embodiment of the invention. For the purpose of reinforcing the terminal sections of the housing additional layers of material may be interposed between inturned ends 66 and the outer wall of the housing.

In the modified arrangement of Fig. 12 the outer wall 85 is formed in one piece and the terminals 86-87 may be turned inwardly. The same 70 side walls 90-91 are used and the inner wall is formed in one piece 92 with an elliptical opening 93. A stitch line 94 secures the flap portions and the ends of the inner wall. At 95 there are shown in broken lines small fastening elements secured 75 adjacent stitch lines 94 for securing to the ends

of the diaper to correct any tendency for the ends of the diaper to fall.

The term "stitching" as used herein and in the appended claims is not limited to joining portions of two blanks by a stitch line produced by a sewing machine but has reference to any joining means. Since the flexible plastic films, either with or without fabric backing, are waterproof and are particularly well suited to the diaper housing of the present invention, various heat sealing or solvent joining means may be used.

The contour of all lines shown in the drawing, whether edges or blanks are stitch lines, is suggestive only and the lines may be varied without departing from the spirit of the invention. For instance, lines 52 on blank 10 which form stitch lines 56 are shown as being straight and slightly non-parallel. The housing would function substantially as well if these lines were more nearly parallel or if they were slightly curved.

While three forms or embodiments of the invention have been shown and described herein for illustrative purposes, and the construction and arrangement incidental to specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

What I claim is:

1. A diaper housing comprising an outer wall, an inner wall having a central elongated opening, and opposed side walls connecting the outer and inner walls, the outer wall being formed from a blank having laterally extending wing portions at each end thereof which are provided with complementary fastening means for attachment around the waist section of the wearer, the side walls being formed from blanks having substantially the shape of a catenary curve whose opposed curved edges are secured to the outer and inner walls along substantially straight lines on such walls, the outer wall and the side walls forming with the inner wall a pocket arranged to receive a folded diaper, the latter wall being arranged to overlie the marginal edges of the diaper while exposing the portion defined by the central elongated opening.

2. A diaper housing comprising an outer wall, an inner wall having a central elongated opening and opposed side walls connecting the outer and inner walls, the outer wall being formed from a blank having laterally extending wing portions at each end thereof which are provided with complementary fastening means for attachment around the waist section of the wearer, the side walls being formed from blanks having substantially the shape of a catenary curve whose opposed curved edges are secured to the outer and inner walls along substantially straight lines on such walls, the opposite ends of such side walls being free and unattached, the outer wall and the side walls forming with the inner wall a pocket arranged to receive a folded diaper, the edges of the latter wall adjacent the opening forming a cover for the diaper.

3. A diaper housing comprising an outer wall formed from a generally rectangular blank having concavely curved side edges, an inner wall structure formed with an elongated central open-

ing and comprising inwardly folded front and rear flaps secured at opposite ends of the outer wall and side wall flaps secured at opposite ends to the front and rear flaps, and side walls formed from blanks generally in the shape of catenary curves secured along their outer edges to the outer wall in substantially straight lines on the latter and secured along their inner edges to the outer edges of the side flaps, the opposed terminal edges of the side wall blanks being free and unattached, and fastening means at the corner sections for attachment around the body of the wearer.

4. A diaper housing comprising an outer wall formed from a generally rectangular blank having laterally extending wing portions at each end thereof, an inner wall structure formed with an elongated central opening and comprising inwardly folded front and rear flaps secured at opposite ends of the outer wall and side flaps secured at opposite ends to the front and rear flaps, such side flaps having generally straight outer edges and concavely curved inner edges, and side walls formed from blanks generally in the shape of catenary curves secured along their outer edges to the outer wall in substantially straight lines on the latter and secured along their inner edges to the outer edges of the side flaps, the opposed terminal edges of the side wall blanks being free and unattached, the inner wall structure being arranged to engage the marginal edges of a folded diaper placed within the housing, and complementary fastening means at the corner sections of the housing.

5. A diaper housing formed from moisture-proof material and comprising an outer wall formed from a generally rectangular blank having laterally extending wing portions at each end thereof, an inner wall structure formed with an elongated central opening and comprising inwardly folded front and rear flaps secured at opposite ends of the outer wall and side flaps secured at opposite ends to the front and rear flaps, and side walls formed from blanks generally in the shape of catenary curves secured along their outer edges to the outer wall in substantially straight lines on the latter and secured along their inner edges to the outer edges of the side flaps, the opposed terminal edges of the side wall blanks being free and unattached, each of said flaps forming the inner wall structure being arranged to engage one marginal edge of a folded diaper placed within the housing while leaving the central section of the diaper open, and complementary fastening means at the corner sections of the housing.
